UNITED STATES PATENT OFFICE.

LEON OTTINGER, OF NEW YORK, N. Y.

LATCH.

1,192,448.

Specification of Letters Patent. Patented July 25, 1916.

Application filed March 26, 1915. Serial No. 17,087.

To all whom it may concern:

Be it known that I, LEON OTTINGER, a citizen of the United States, and a resident of the city of New York, county and State 5 of New York, have invented certain new and useful Improvements in Latches, of which the following is a full, clear, and exact description.

My invention relates to latches for doors 10 where it is desired to provide means for automatically operating a latch to fasten a door upon closure of the same and at the same time to enable a slight movement between the door and the casing without any 15 liability of the door working loose, or of opening unintentionally.

My invention is particularly applicable to 20 doors for automobiles where the spring or elasticity of the chassis causes the door to move slightly in its casing without looseness.

It also comprises means in connection 25 with the latch so that the parts are always held under spring pressure, the pressure being exerted in every direction in which there is liable to be a movement between the door and the casing.

My invention also comprises means for 30 preventing the door from being accidentally pushed open by pressure from the inside, while at the same time if it is desired to open the door the same may be accomplished by a comparatively slight pressure upon the handle or knob provided for that purpose.

Further advantages and functions of my 35 improved latch will be hereinafter more fully pointed out in the specification and claimed in the accompanying claims.

For a detailed description of one form of 40 my invention, which I at present deem preferable, reference may be had to the following specification and to the accompanying drawings forming a part thereof, in which:

Figure 1 is a vertical sectional view of a 45 door casing and door, showing the parts of my improved latch in elevation therein and in their locked or latched position. Fig. 2 is a similar view, but showing the parts in their unlocked or unlatched position. Fig.

50 3 is a horizontal sectional view of a door and casing, taken substantially on the line III-III, Fig. 1, showing the latch member also in section, the parts of the latch being in their engaged or locked position. Fig. 4 55 is a similar view to Fig. 3, but showing the parts of the latch in unlocked position, and

the door slightly open or separated from the casing. Fig. 5 is a fragmentary horizontal sectional view of the door and casing taken substantially on the line V-V, Fig. 1, and 60 showing the parts of the latch in plan view. Fig. 6 is a similar view, but showing the door and casing slightly separated. Fig. 7 is a vertical sectional view of the door casing taken substantially on the line 65 VII-VII, of Fig. 1, showing the door itself in elevation and the latching member in section.

Referring to the drawings, the numeral 1 indicates the body of a door, and the numeral 2 indicates the door casing or jamb which with the socket or recess therein, constitutes the latch engaging member. The parts of the latch are preferably mounted on a suitable frame or casing 3 which is 75 seated in a suitable recess in the body of the door, in the well known way.

The numeral 4 indicates the sliding bolt or latching member proper which is adapted to project through a suitable slot to engage a recess 5 in the door jamb 2. The necessary spring pressure to hold the latch 4 in extended or withdrawn position is provided by a spring-pressed plunger or head 6 mounted in a spring barrel or tube 7 which 80 is pivoted on a rib or elongated lug 8 and contains the helical spring 9 which contacts with and forces outwardly the plunger 6. The plunger head 6 is connected with a pivoted plate 10 by means of a pin 11 working 85 in an elongated opening 12 in the plate 10. The plate 10 constitutes a bell crank lever and has a downwardly projecting arm 13 provided with rounded bearing surfaces 14 and 15, the latter being adapted to contact 90 with a flange or projection 16 on the rear of the latching member 4, and the bearing surface 14 being adapted to engage a projection 17 on the central part of the latching member 4. Said projection 17 does not 95 extend upward as far as the projection 16, thereby allowing the arm 13 of the plate 10 to pass above the same when the latch member is in extended position, as shown in Fig. 1. When the latch is in its withdrawn 100 position, the arm 13 is located between the projections 16 and 17 and a movement of the plate 10 about its pivot 18 will cause a corresponding horizontal movement of the latching member 4. The bearing surface 14 105 disengages the projection 17 when the latching member is in a position approximately

one-half way between the position of the plate 10, shown in Fig. 2, and that shown in Fig. 1. The projection 17 constitutes a limiting check or stop which prevents the 5 latching member being forced inward by external pressure for the reason that when the plunger has been forced in to the limit of the slot 12 the plate begins to rotate and causes the arms 13 to strike against the projection 17.

The plunger head 6 is provided with a laterally projecting lug or arm 19 which moves into place behind the latching member 4 as the latter passes toward its extended position. The pressure of the spring thereupon 15 will be applied to the latching member 4 through said lug 19 and project the latching member farther outward, where it is thereafter held under spring pressure. It should 20 be noted that the location of the pivot pin 11 which connects the plate 10 with the plunger head 6 constitutes a toggle which maintains the plate in either of two positions on each side of the line connecting the 25 said pivot 18 with the rib 8. In this manner the latching member 4 will be consequently held in either its extended or withdrawn position, depending on the relation 30 of the plate 10 and the spring barrel 7.

As a means to cause said plate 10 to rotate so as to withdraw the latching member 4, I provide a transverse angular shaft 20 which passes transversely through the casing and carries on its outer end a lever or 35 other handle 21. Upon the angular rod 20 is fixed an arm 22 which is adapted to contact with the lower side of the spring barrel 7 by means of the handle 21. This is indicated in Fig. 1. A movement of the 40 handle toward the right causes upward movement of the arm 22, thereby forcing the spring barrel 7 upward until it assumes the position shown in Fig. 2, thus withdrawing the latching member.

When it is desired to provide a key-operated lock for the latch, I provide a lock barrel of any suitable type, such as that indicated by the numeral 23, which controls the position of an arm or lever 24. When 50 this is in the position shown in dotted lines in Fig. 1, it obstructs the path of the spring barrel 7, thereby preventing the arm 22 from forcing the said spring barrel upward when the handle 21 is operated. I also preferably provide a bow or similar spring 55 which maintains the arm 22 in its inoperative position, and at the same time contacts with a projection 26 extending from the latching member 4. The spring 25 thereby tends to maintain the said latching member 60 4 in its correct position and prevents rattling thereof.

The handle 21 is primarily intended, when the latch is used on an automobile door, to 65 be operated from the inside of the body, and

to provide means for operating the latch from the outside of the body, I provide a transverse rod or shaft 27 which carries a projecting arm 28, the rod 27 having on its outer end a knob or handle 29, as indicated 70 in Fig. 7. The arm 28 is adapted to contact with an angular projection 30 on the plate 10 and its movement rotates said plate, thereby producing the same effect to withdraw the latch as does a movement of the 75 handle 21. The rod or shaft 27 is located in the position shown in order to provide unobstructed space for the lowering of the window of a limousine or similar inclosed car. Otherwise, of course, the knob or 80 handle 29 may be placed on the outer end of the shaft 20.

The latch member 4 is extended or thrown into its engaged position automatically when the door is closed. This is accomplished by 85 the following parts: Pivoted on the latch-casing 3 is a sector-shaped lever 31 adapted to project inward through a slot in said casing 3 (see Figs. 1, 5 and 6). The opposite side of the sector 31 extends into the path 90 of a projection 32 on the plate 10, as indicated in Fig. 1. A spring 33 has one end bearing against said sector 31 and its other end bearing upon the projecting arm 28. This tends to keep said sector 31 constantly 95 in its extended position whether the projection 32 is in engagement therewith or not.

By referring to Figs. 5 and 6, it will be seen that when the door is closed, the sector 31 will come in contact with the door stop 34 on the door jamb and be pressed inward from the position indicated in Fig. 2, thereby causing the toggle formed by the plate 10 and the spring barrel 7 to pass its neutral point and consequently force the 105 latching member 4 outward, where it is maintained under spring pressure by the lug 19, as above described.

In order to hold the latching member 4 under spring pressure in all directions, the 110 outer end of the same is bifurcated and has pivoted between the sides thereof, a hook-shaped lever 35 which may be termed a wedging portion or member, the curved inner end 36 of which is adapted to bear 115 against the inner side of the casing 3, and the outer end thereof against one side of the recess 5, as indicated in Fig. 3. The lever 35 being pivoted at 37, an outward movement of the latching member 4 will cause 120 a pressure on the hooked end 36 which will produce a pressure on the opposite straight end of the lever in a direction transverse to the lock, thereby tending to force the door more tightly toward its closed position and 125 prevent rattling when the door is used on an automobile or in any other place where looseness is objectionable. By this arrangement movement of the latching member 4 relative to the door jamb 2 is permitted in 130

every direction under spring pressure, the means for producing the same being provided by the spring 9 in the spring barrel 7. This arrangement also obviates the use of rubber buffers on the door stop, heretofore almost universally used, and acts in a manner similar to that of a wedge to force the door against its stop. That is, the transverse pressure is proportioned to the force 10 acting longitudinally on the latching member.

Supposing the latching member 4 (Fig. 3) is being forced constantly toward the left under spring pressure, movement of the 15 door body 1 to the right or to the left, toward or away from the jamb or casing 2 does not affect the latch. Similarly, a movement of the door 1 in a vertical direction (Fig. 1) relative to the casing 2, has no effect, and also a movement transverse of the 20 door 1 (Fig. 5) is permitted without affecting the latching member.

The numerals 38 and 39 indicate the ribs on the door and door casing, respectively, 25 forming guides to aid the registering of the said parts, particularly if the door has a tendency to sag by reason of the wear or distortion of the hinges thereon.

It should also be noted that it is impossible to have the latching member or bolt 4 extended while the door is being closed, in which case it would obviously injure the door jamb or break the bolt. Furthermore, the bolt must be entirely withdrawn when 35 the door is opened and so maintained until the door is closed again. This effect is produced by reason of the fact that the arm 13 (Fig. 1) must first move until it contacts with the projection 16 before the latch 4 begins to be withdrawn, and thereafter the 40 pin 11 passing its neutral point causes the spring 9 to completely withdraw the latch and so maintain it. Thus the direct pressure of the spring is first removed from 45 the latch and transferred to the bell-crank lever allowing the latch to slide easily to its withdrawn position. In extending the latch when the door is closed, the converse is true.

It should be noted that either of the handles 21 or 29 may be operated to withdraw the latch without affecting the other handle. It should also be noted that when the door is being closed and the latching bolt thereby forced to its extended position, neither of 55 the operating handles is oscillated.

I do not wish to be limited to the details of form and arrangement of parts herein set forth, for various changes may be made without departing from the spirit and scope 60 of the invention as set forth in the following claims.

Having described my invention what I claim and desire to protect by Letters Patent is:

65 1. A latch comprising a latching member,

an opposed latch-engaging member, a handle for withdrawing said latching member, a spring for holding said latching member under oppositely acting spring pressure when in retracted and extended positions, 70 and means carried by said latching member to wedge the same within said latch-engaging member under spring pressure when the parts of the latch are engaged.

2. A latch comprising a latching member, 75 a handle for withdrawing the same, an opposed latch-engaging member, a spring for holding said latching member under pressures acting in opposite directions when in retracted and extended positions, and means 80 for transmitting the outward pressure of said member transversely thereof when in latched position.

3. A latch comprising a latching member, 85 a handle for withdrawing the same, an opposed latch-engaging member, a spring for holding said latching member under pressures acting in opposite directions when in retracted and extended positions, and a connection between said spring and said handle 90 to shift said spring to withdraw said latching member when said handle is operated.

4. A latch comprising a latching member having a wedging portion, a spring acting to hold the same under positive spring pressure in both retracted and extended positions, a trip connected with said member and adapted to move said latching member to its extended position, and an opposed latch-engaging member adapted to receive 100 the wedging portion of said latching member and to be held under spring pressure by the action of said spring.

5. A latch comprising a latching member, 105 an opposed latch-engaging member, means for holding said latching member under spring pressure acting in opposite directions when in retracted and extended positions, means operated by said latch engaging member for tripping said latching member, a 110 handle, and a connection between said latching member and handle for retracting said member, said connection being inoperative when said latching member is being extended.

6. A latch comprising a latching member, 115 a spring for holding the same yieldingly under spring pressure in extended and retracted positions, an opposed latch-engaging member, a trip operated by the latter 120 to positively move said latching member to its engaged position, a handle mounted adjacent said latching member for retracting the same, and a connection acting in one direction between said handle and said latching member, said connection being inoperative when said latching member is being extended.

7. A latch comprising a latching member, 125 an opposed latch-engaging member, an oper-

- ating handle, a spring for holding said latching member in yielding engagement with said opposed member, means connected with said handle for causing the reverse of the outward pressure of said spring on said latching member and for withdrawing the same, and means carried by said latching member for producing a transverse yielding pressure on said latch-engaging member.

5 10 15 20 25 30 35 40 45 50 55 60 65 70 75 80 85 90 95 100

13. A latch comprising a latching member, an opposed latch-engaging member, a spring connected with said latching member and acting to hold the same under positive spring pressure in both retracted and extended positions, a trip operating on said latching member and arranged to shift the action of said spring by contacting with said latch-engaging member to force said latching member outward.

14. A latch comprising a latching member provided with a recess having walls of unequal height, a bell-crank lever one of whose arms is adapted to enter said recess, a pivoted spring acting upon the other arm of said lever to maintain the same upon opposite sides of a medial line, an opposed latch-engaging member, a trip adapted to contact therewith and acting on said bell-crank lever to extend said latching member, and a lug connected with said spring and adapted to exert the force of said spring directly on said latching member when the latter is disengaged from the bell-crank lever and in its extended position.

15. A latch comprising a latching member, an opposed latch-engaging member, a spring for holding said latching member extended, a lever connecting said spring and said latching member, means for disengaging said lever from said latching member for a portion of its movement, and means for transferring the pressure of said spring directly to said latching member during said portion of its movement.

16. A latch comprising a latching member, an opposed latch-engaging member, a spring for holding said latching member under positive spring pressure in both extended and retracted positions, a lever connecting said spring and said latching member, means for disengaging said lever from said latching member for a portion of its movement, and means for transferring the pressure of said spring directly to said latching member during said portion of its movement.
